UNITED STATES PATENT OFFICE.

WARREN WILLIAMS AND HOBART M. WILLIAMS, OF LORDSBURG, CALIFORNIA.

PUMP-HEAD.

SPECIFICATION forming part of Letters Patent No. 760,596, dated May 24, 1904.

Application filed October 15, 1903. Serial No. 177,162. (No model.)

To all whom it may concern:

Be it known that we, WARREN WILLIAMS and HOBART M. WILLIAMS, citizens of the United States, residing at Lordsburg, in the county of Los Angeles and State of California, have invented a new and useful Pump-Head, of which the following is a specification.

This invention relates to devices employed for operating pumps, more particularly the pumps of deep wells, which require strong force to actuate their plungers, and has for its object to simplify and improve the construction, whereby a relatively strong upward movement and a relatively rapid downward movement is imparted to the plungers without increasing the complication or number of the parts or otherwise adding to the expense or weight of the operating machinery; and the invention consists in certain novel features of construction, as hereinafter shown and described, and specified in the claims.

In the drawings illustrative of the invention, in which corresponding parts are denoted by like designating characters, Figure 1 is a side elevation, partially in section, of the device applied. Fig. 2 is a side elevation, and Fig. 3 is a transverse section, enlarged, of a portion of the operating-arm and sliding block detached.

The improved device consists of a base-frame 10, preferably of cast-iron, and mounted upon a supporting-frame 11 of any suitable form to secure the proper height above the ground.

Pivoted in a suitable standard 12 upon one side of the base-frame 10 is a beam 13, preferably formed with lateral ribs 14 along its upper and lower edges, whereby a substantially H-like form is produced in cross-section, as shown, to combine lightness and strength. Mounted slidably upon the beam 13 and enclosing its lower side and also the edges of the lower lateral ribs 14 is a block 15, having a transverse bearing 16, as shown.

The pump-rod is represented at 17 and is pivoted to the free end of the beam 13, as at 18, and operates the pump-plunger (represented at 19) within the pump-cylinder, (represented at 20.)

Mounted for rotation upon the base-frame 10 between the plunger-rod 17 and beam-standard 12 is a shaft 21, carrying a relatively large gear-wheel 22, the latter preferably for rotation by a gear-pinion 23 on the main power or driven shaft 24, the pinion being supported upon the base-frame 10 by bearings 25, as shown.

The gear-wheel 22 is provided with a crank or "wrist" pin 26 for engagement with the bearing 16 in the block 15. The gear 22 is also provided with one or more graduated sockets 27 for the wrist-pin 26, so that it may be adjusted to vary the "throw" of the beam, and thus correspondingly vary the stroke of the plunger. By this simple arrangement it will be obvious that when the wheel 22 is rotated in the direction of the arrow the beam 13 will be vibrated upon its bearing 12 and alternately elevate and depress the plunger 19, and it will also be noted that at the beginning of the upstroke the crank-pin has moved the block toward the free end of the beam and nearest to the pump-rod. Hence the "lift" is almost directly upon the rod and travels the next one-third or more of the upstroke with a strong and powerful leverage, but at a relatively slow speed; but as the block is carried over by the wheel and begins its return movement it engages the beam between the wheel and its pivot and necessarily acting upon a shorter arc of the movement of the beam returns the beam downward in a much shorter period of time and correspondingly carries the plunger downward more rapidly than it elevates it. The upstroke carries the load and requires the greatest force, while the return stroke, carrying no load, requires much less force, and consequently the return stroke can be made more rapidly and without detriment to the apparatus. A material saving of time and conservation of force are thus obtained with a very simply constructed and easily applied and operated device.

As hereinbefore stated, this device is specially applicable to pumping mechanism for deep wells, for mines, and the like, where the load to be lifted is quite heavy. It is there-

fore of importance to use a working beam which shall be capable of carrying a comparatively heavy load, and hence important to avoid weakening such beam—such as, for instance, by slotting the same for the accommodation of the crank-pin or for a boxing connected with the latter. By the construction herein set forth the boxing connected slidably with the working beam possesses great strength, and the beam itself, while of a comparatively light structure, will possess great strength proportionately to the width thereof.

Another important feature of this construction is that the box journaled upon the crank-pin and connected slidably with the working beam will bear directly upward against the under side of said beam. This is of great importance, especially on the upstroke of the beam when the latter is carrying a heavy load and when it is of extreme importance that the working beam shall not be capable of bending or yielding under the pressure of the load.

The invention as herein described is especially applicable for the purpose of operating deep wells, and we find that an important advantage is gained by practically avoiding an intermittent or pulsating discharge of the fluid elevated, for the reason that a relatively short time is occupied in accomplishing the downstroke of the piston, which latter during the greater portion of the time is moving upwardly, and consequently raising the fluid, which thus will be discharged in a practically constant stream.

If required, two or more of the devices may be employed in connection with one well and preferably operating alternately; but this would not be a departure from the principle of the invention, as it would not affect the operation or the functions of the parts.

Having thus described the invention, what we claim is—

1. In a pump-operating mechanism, a pivotally-mounted working beam, a boxing moving slidably upon said beam in contact with the under side of the same, a shaft mounted for rotation between the ends of the beam, a wheel upon said shaft and a wrist-pin connected with said wheel and engaging the slidable boxing.

2. In a pump-operating mechanism, a pivotally-mounted working beam provided with laterally-extending flanges, a boxing mounted slidably in contact with the under side of the beam and enveloping the lower lateral flanges of the same, a shaft mounted for rotation upon the frame between the ends of the beam, a wheel upon said shaft, and a wrist-pin connected with said wheel and engaging the slidable boxing.

In testimony that we claim the foregoing as our own we have hereto affixed our signatures in the presence of two witnesses.

WARREN WILLIAMS.
